TELEPHONE SYSTEM

Owen Avis Pearce, Barnston, England, assignor to
 Associated Telephone & Telegraph Company,
 Chicago, Ill., a corporation of Delaware

Application December 8, 1937, Serial No. 178,662
 In Great Britain January 19, 1937

5 Claims. (Cl. 179—18)

The present invention relates to telephone or like systems and is more particularly concerned with finder switch arrangements for use therein for connecting a calling subscriber's line to a first numerical switch. The chief object of the invention is to provide an economical and efficient allotting scheme which can be applied with advantage in all types of finder switch systems and which obviates the need for separate rotary 10 switches for allotting purposes.

According to one feature of the invention in a telephone system employing finder switches for connecting a calling line to a first numerical switch a variable number of finders are adapted 15 to operate simultaneously under the control of a start relay connected in a bridge circuit.

According to another feature of the invention in a telephone system employing finder switches for connecting a calling line to a first numerical switch finder switches are allotted for use under 20 the control of a single set of common equipment adapted to allot a plurality of finders successively at intervals which are small compared with the time required for a finder to complete its operation. 25

A further feature of the invention is that in a telephone system employing finder switches for connecting a calling line to a first numerical switch a finder is allotted for use in response to 30 a momentary start impulse transmitted thereto from common equipment which is adapted to transmit an impulse to a further finder before that originally started has completed its operation in the event of simultaneous calls in a group.

The invention will be better understood from the following description of one method of carrying it into effect, reference being had to the accompanying drawings comprising Figs. 1 and 2. These should be arranged side by side to form a 35 circuit diagram of a portion of a finder switch system in which the switch mechanisms employed are all assumed to be of the longitudinal and rotary type disclosed in the application of Robert N. Saxby, Serial No. 54,287, filed December 13, 1935. The general principles of the system follow those described in Taylor Patent No. 1,914,540 of June 20, 1933, whereby primary line finders are arranged so that those first taken into use (first choice finders) are directly connected to first 40 group selectors while those last taken into use (last choice finders) are arranged to be connected to first group selectors in a common group over secondary finder switches. The primary and secondary start and control sets and associated allotter switches which are normally pro-

vided in systems of this type have been replaced by so-called primary and secondary start relay sets, each comprising two relays only. Each individual finder switch is provided with all the necessary relays for setting and control purposes, contacts of one relay in each switch being also utilised in connection with a chain circuit allotting arrangement. The necessary changes of connection according to the conditions under which the finders are to be used are all made at 10 the intermediate distributing frame IDF, no strapping changes having to be made internally. Thus the circle and dash connections shown are suitable for first choice primary finders which are directly connected to first selectors and also for 15 secondary finders which are assumed to be identical with the primary finders while the dotted connections apply to last choice primary finders which are connected with first selectors by way of the secondary finders. 20

Considering now the circuit operation, when the subscriber whose line circuit is shown removes his receiver, the loop placed across the incoming speaking leads operates relay L. Thereupon armature *l1* disconnects the winding of 25 relay K from the P lead extending to the final selector bank multiple and applies a busy earth thereto, while armature *l2* and *l3* mark the position of the calling line in the rotary and vertical bank multiples respectively of the line finders serving the particular 200-line group involved, it being understood that the upper and lower sets of contacts on the vertical bank extend individually to common leads VBA and VBB respectively 30 which are each common to a level of twenty subscribers. At the same time armature *l4* connects battery over resistance YA, which is common to the twenty subscribers on the calling level, to the primary start leads PSL which is common to the group of 200 subscribers. The common start relay PS is thereupon operated and at its armature *ps1* completes an energising circuit for relay SR which is slow both to operate and release. Assuming that none of the other line finders serving 35 the group in question is at present in use, earth is also extended during the operating time of relay SR over armature *sr1* to operate relay A in the finder circuit shown which represents the first finder in the chain allotting circuit. 40

Relay A upon operating, at armature *a3* completes a locking circuit for itself in series with the lower winding of relay B which however cannot yet operate since it is short-circuited by the earth extended from the start relay set. On the operation of relay SR after a short period, it opens its 45 50 55

own energising circuit at armature $s72$ but due to its slug it does not release until a further short interval has elapsed. During this time the earth shunt is removed from the winding of relay B which now operates in series with relay A which remains held and thereupon armature $b2$ connects battery through resistance YB, which is individual to the finder switch, to common lead X extending to the bridge circuit in the start relay set. Since it is arranged that resistances YA and YB are equal and resistances YC and YD are also equal, the bridge will now be balanced and no current will flow through relay PS which therefore releases. Thus on the subsequent release of relay SR there will be no earth to re-energise it and it will then remain normal. Relay B also at armature $b4$ extends the finder start lead over lead 11 to the second finder in the chain in preparation for further calls, while at armature $b3$ it completes a self-interrupted driving circuit for the finder vertical magnet VM from earth over armatures $v71$ and $a3$, contacts $NP1$ and $NR1$, armatures $b3$ and $a2$, vertical magnet interrupter contacts vm , magnet VM to battery.

Accordingly the wipers of the finder are raised step-by-step until the vertical wiper VW encounters the level marking battery via resistance YE whereupon relay VT quickly operates and at armature $v71$ disconnects the magnet driving circuit and at the same armature opens the holding circuit of relay A, relay B now being maintained operated over its upper winding. Meanwhile on the first vertical step of the finder the off-normal springs were mechanically operated and at contacts $N2$ served to prepare a circuit for the rotary magnet RM and at contacts $N3$ to maintain a chain circuit to the second finder. On release of relay A after its slow period a self-interrupted driving circuit is completed for the rotary magnet RM from an earth which is connected to common lead 10 by way of delayed alarm equipment which gives an alarm if the magnet remains energised for more than a predetermined period, rotary magnet interrupter contacts rm , off-normal contacts $N2$, armatures $a1$, $ha5$ and $hb5$, magnet RM to battery. Accordingly the wipers are rotated in search of the calling line. On the first rotary step the rotary off-normal springs are mechanically operated and since the finder taken into use is a first choice finder battery through resistance YF is connected over armature $b9$, rotary off-normal contacts $NR4$ and I. D. F. cross connection to the positive line of the group selector whereupon the A and B relays therein are operated and return a guard earth over the P conductor.

When the calling line is found, a circuit is completed to lock the rotary magnet RM which holds its armature in the operated position and thus arrests the motion, this circuit extending from earth, armature $b7$, rectifier MRA or MRB in a conductive direction, left-hand low resistance winding of either relay HA or HB, wiper and bank M1 or M2 in accordance with the bank on which the calling line is situated, armature 12 of the calling relay L, the calling level on the lower section of the vertical bank, vertical wiper VW, armature $b1$, rotary magnet interrupter contacts rm in the operated position to battery via the magnet RM.

Assuming that the marking is on the M1 bank, relay HA is operated in this circuit and at armature $ha5$ locks over its right-hand high resistance winding in series with the rotary magnet which

now releases, at armatures $ha1$, $ha2$ and $ha3$ extends the first set of negative, positive and private wipers through to the first selector, at armature $ha4$ disconnects any circuit for relay HB and at armature $ha6$ extends earth from the P conductor to short-circuit the upper winding of relay B thereby bringing about its release. Relay B thereupon at armature $b1$ opens a further point in the rotary magnet locking circuit, at armature $b2$ disconnects the resistance battery YB from the bridge circuit and at armature $b8$ opens the circuit of relay VT which releases. During this time the extension of the P conductor through from the first selector will have brought about the operation of the calling subscriber's cut-off relay K from the guard earth and this relay releases relay L and connects earth to the subscriber's meter MTR in readiness for metering. The release of relay L removes the vertical and rotary markings and disconnects the resistance battery YA from the PSL lead. Relay PS will therefore remain normal until another call is originated since it is arranged that the removal of the resistance battery YB from the X lead on release of relay B takes place at approximately the same instant as relay L releases.

If the calling party had been connected to the M2 bank, relay HB would have been operated to switch through the second set of wipers, while if two calling lines are encountered in the same position the first of the relays HA and HB to operate will disconnect the circuit of the other one.

If two or more subscribers in any group originate calls at the same time, one line finder will be started up for each level calling. Should, for example, three subscribers on different levels originate calls simultaneously, then three resistance batteries will be connected in parallel to the start lead PSL. Hence on the operation of relay B in the first finder selected, the PS bridge will remain unbalanced and relay PS will remain operated. Relay SR on releasing will therefore have its circuit again completed and the second finder in the chain will therefore be started up. The cycle of operations will in this case continue until three finders have been started up whereupon the three resistance batteries connected in parallel to the X lead via the armatures of the B relays in the three finders concerned will balance the bridge and release relay PS. Thus it will be appreciated that if calls should be originated by subscribers on as many as ten different levels of the finders at any one time, a corresponding number of finders would be started off at intervals of the order of fifty milli-seconds only, the intervals representing the approximate time for relay SR to operate and release. If however, two or more subscribers on the same level call together, one finder only will be started off as is the usual practice. Immediately this finder switches through to one of the calling subscribers, a second finder will be started off and so on until all the calling parties have been connected through to first selectors. The same considerations apply to the starting up of secondary finders by last choice primary finders when the latter are brought into use in a manner now to be described.

When all the first choice finders have been taken into use, the chain allotting circuit extends naturally to the first of the last choice finders serving the group. As previously mentioned the last choice finders of each group of subscribers in the exchange are not directly connected to selectors but are connected by way of secondary

finders to a common group of first selectors. The secondary finder starting and chain allotting arrangements are identical with those provided for the primary finders and thus it will be appreciated that the last choice finders operate with respect to the secondary finders in the same way as calling line circuits with respect to the primary finders. The secondary finders are assumed to be of the 200-line type so that for exchange maintenance purposes they are interchangeable with the primary finders. A circuit diagram of a secondary finder has therefore not been shown since it is identical with the primary finder indicated and its outgoing leads are connected over the I. D. F. to a group selector in the same manner as those of a first choice primary finder.

Considering now the circuit operation, when relay PS is again operated on the origination of a further call, the first last choice finder in the allotting chain circuit is started up and it thereupon functions in the normal manner until it cuts into the marked level and commences to hunt in a rotary direction. The rotary off-normal springs now at contacts NR2 and NR3 complete connections over the I. D. F. cross connecting leads to mark the position of the calling last choice finder in the vertical and rotary bank multiples respectively of the secondary finder switches, while the resistance battery YG which is similar to the level marking battery YH in that it is common to the twenty last choice finders on the calling level of the secondary finders is connected over the I. D. F. by way of armatures *a*2 and *b*3 and contacts NR1 to the common secondary start lead SSL serving the group of 200 last choice finders. Relay SS in the secondary finder start group is thereupon operated and in the same way as relay PS it starts up the first secondary finder in the chain to search for the calling last choice primary finder. In the meantime the latter continues its search for the calling line and when it is found either relay HA or relay HB is operated and switches the calling line through to the outgoing leads. No earth will be extended over the P conductor however to operate the calling subscriber's cut-off relay K and to short-circuit relay B until the secondary finder finds the calling last choice finder. When the secondary finder finds the marked position, relay HA or HB therein operates whereupon the calling line circuit is switched right through the primary and secondary finders to the group selector connected to the latter whereupon earth will be extended back to shunt down the B relays in both the finders and at the same time to operate the cut-off relay K. All vertical and rotary markings in the two finder banks are now removed and the potentials applied to the common leads PSL, X, SSL and Y are disconnected in preparation for a further call.

When the complete train of automatic switches has been set up and the wanted party replies, a booster battery metering pulse is extended back along the P conductor and this feeds through rectifier MRA or MRB according to whether relay HA or HB has been operated, and it operates the calling party's meter MTR over either the M1 or the M2 lead in well-known manner.

On the release of the connection at the end of conversation, earth is removed from the P conductor by the controlling switch in the train thereby releasing the operated switching relay in the finder or finders brought into use and also relay K in the calling subscriber's line circuit. A self-interrupted driving circuit is now com-

pleted for the rotary magnet in the finder or finders as the case may be from the release alarm conductor 10, so that the wipers are rotated clear of the banks after which they fall vertically and restore below the banks to the normal position where the driving magnet circuit is opened at the off-normal contacts N2. The off-normal contacts N3 then re-connect the chain allotting lead to the finder so that if there are no other earlier finders in the chain which are also free for use, this finder will be taken into use on the origination of another call.

Should the calling party restore his receiver before the finder taken into use has completed its vertical movement, the vertical and rotary bank markings will be removed but since relays A and B remain locked the finder will continue to step vertically until it reaches the 10th level. On this level the normal post springs NP are mechanically operated by the switch shaft and at contacts NP1 complete a locking circuit for the vertical magnet VM via the current limiting resistance YJ and at the same time open the series holding circuit of relays A and B. If there is a battery marking potential provided on this level by another calling subscriber, relay VT will operate and the switch will cut in and search in a rotary direction in a normal manner. If however no marking is encountered, relay VT will not be operated and the vertical magnet will remain locked until relay A releases when the switch will cut in, rotate its wipers clear of the banks, and restore to normal, no testing taking place during rotation since relay B is normal and no earth is therefore supplied to relays HA and HB. If the calling party should hang up during the rotary motion the finder will merely continue to rotate until the wipers are clear of the banks and will then restore.

If the first group selector associated with a primary finder is artificially busied for testing purposes by the connection of earth to the P conductor, relay B in the primary finder is operated over its upper winding, thereupon preventing the finder from being taken into use by extending the chain allotting circuit at armature *b*4 to a succeeding finder. Similar considerations apply to the busying of a group selector associated with a secondary finder. The primary and secondary finders may be artificially busied directly by shifting the link T from the upper set of test jack springs to the lower set so that the chain allotting circuit is extended through to the next switch in the chain.

I claim:

1. In a telephone system, lines, first numerical switches, finder switches having access to said lines, a start relay connected in a balanced bridge circuit and controlled from calling ones of said lines to cause a variable number of said finders to operate simultaneously to connect calling lines to said numerical switches, said bridge circuit balanced whenever there are as many finders started as there are lines calling.

2. In a telephone system, lines, finder switches having access to said lines for extending connections therefrom, a common equipment responsive to a call from one of said lines to transmit a momentary start impulse to one of said finders to cause said finder to find said calling line, said common equipment operated responsive to a second call from one of said lines to transmit a start impulse to a second one of said finders before the first finder has completed its operation to find the first calling line.

3. In a telephone system, a group of lines, a plurality of finder switches having access to said lines, a common start relay responsive to calls from said lines to start said finder switches by a momentary impulse transmitted to a finder switch, a relay in each finder switch slow to operate and slow to release, said relay having means for breaking its own circuit and also having means for cutting off the start impulse to the finder switch.
4. In a telephone system, lines, finder switches having access thereto, a start relay common to said lines, a chain start circuit, means responsive to a call from one of said lines for establishing a calling position to operate said start relay to transmit a momentary impulse over said start circuit to start one of said finders to find the calling line, means responsive to the operation of the finder to extend the start circuit to the next available finder switch, the calling condition in said line being maintained until the line is seized by

a starting finder, and means for neutralizing said calling condition in the starting circuit to insure starting only as many finders as there are lines simultaneously calling.

5. In a telephone system, a group of lines divided into sub-groups, a group of finder switches having access to said lines, a start relay common to said lines and responsive to calls from said lines to cause the simultaneous operation of a plurality of finder switches to hunt for calling lines, a bridge circuit for said start relay, a branch of said bridge circuit for each sub-group of lines including a battery feed through a resistance, another branch circuit including a battery feed through a resistance for each finder switch in operation, said bridge circuit balancing and preventing the starting of more finders when the number of calling sub-groups equalize the numbers of finders in operation.

20

OWEN A. PEARCE.
